(57) **CLAIM**

The ornamental design for a charging device for an electric vehicle, as shown and described.

DESCRIPTION

FIG. 1 is a perspective view of a charging device for an electric vehicle, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of area 'A' circumscribed within FIG. 1;

FIG. 10 is a perspective view thereof, showing the device in a state of use;

FIG. 11 is an enlarged view of area 'B' circumscribed within FIG. 3;

FIG. 12 is an enlarged view of area 'C' circumscribed within FIG. 3; and,

FIG. 13 is an enlarged view of area 'D' circumscribed within FIG. 3.

In the drawings, the dash-dash broken lines illustrate portions of the article that form no part of the claimed design. The dash-dot-dot broken lines illustrate the boundary of the portion shown enlarged in FIGS. 9 and 11 to 13. The unshaded regions form no part of the claimed design.

1 Claim, 13 Drawing Sheets
